METHOD FOR DETERMINING BRAN IN
CEREAL FLOUR

Roger A. Larkin, Peoria, Ill., assignor to the
United States of America as represented by the
Secretary of Agriculture

No Drawing. Application July 8, 1952,
Serial No. 297,800

7 Claims. (Cl. 73—432)

(Granted under Title 35, U. S. Code (1952),
sec. 266)

1

A non-exclusive, irrevocable, royalty-free license in the invention herein described, for all governmental purposes, throughout the world, with the power to grant sublicenses for such purposes, is hereby granted to the Government of the United States of America.

The invention relates to a method for determining the presence of bran and germ particles in wheat flour. It relates, particularly, to a method for determining such particles in cereal flour or in similar comminuted compositions by a simple dye technique. As will be explained in detail below, the method is more accurate and definitive than prior methods for evaluating flours.

The degree of refinement of a cereal flour may be measured by the completeness of the separation of the bran and germ constituents from the endosperm and resultant flour. Evaluation of flours to determine the degree of refinement has long been a problem of considerable economic significance. Prior methods have frequently involved such indirect determinations as ash content, color tests, or combinations of both. Pentosan content has also been suggested as a test. The prior methods of evaluation have required complicated and rather tedious techniques and have not provided satisfactory criteria, all being somewhat empirical in character.

It has been discovered, in accordance with this invention, that Crystal Violet dye when applied to a flour sample stains the germ and the bran layers and protein of the endosperm, but does not stain the endosperm cell walls. Such a dyed sample may be treated with a strong base such as sodium hydroxide or potassium hydroxide in aqueous solution to leave the bran and germ fragments stained distinctively, the remainder of the sample having been rendered colorless by the base.

Utilizing these discoveries, a simple procedure has been developed which affords a rapid and reliable determination of the bran and germ content of cereal flours or of cereal flour mixtures, or even of baked or otherwise finished food products consisting mainly of flour. In general, the method comprises applying a dilute aqueous solution of the dye to the sample, subsequent treatment with aqueous alkali and then separation of the liquid medium followed by final observance of the solid residue. The bran and germ particles, after this treatment, appear violet in color. Endosperm cell walls, incompletely dispersed starch and incompletely dispersed protein which may also be present in the solid residue are color-

2

less. The alkali treatment produces a differential decolorization, and the decolorizing action is stopped at a point before bran and germ particles have been decolorized and after the other materials in the mixture have become colorless. The bran and germ content of the flour sample may be determined visually, i. e., by estimating the relative proportion, by counting the fragments, or by any other visual method as desired.

The invention possesses several advantages over prior evaluating methods. For example, it does not depend upon a gravimetric or other kind of chemical analysis. It may be carried out in considerably less than 2 hours' time, requires no special equipment, except a microscope, and does not require highly trained personnel.

The following procedure is a preferred method of carrying out the invention.

- 20 1. A weighed sample of flour is wet with ethanol, preferably 95 percent ethanol.
- 25 2. Crystal Violet dye is applied in the form of 0.04 to 0.07 percent aqueous solution. Sufficient dye should be added to form a watery suspension or at least a thin slurry.
- 30 3. After permitting the dye mixture to stand for about 10 minutes, sufficient 0.25 N sodium hydroxide is added to disperse the starch and protein.
- 35 4. After standing for about 5 minutes, an approximately equal volume of distilled water is added, and the mixture stirred and let stand for about 1 hour.
- 40 5. The mixture is filtered, preferably using white filter paper.

35 The bran and germ particles appear violet in color upon the white filter paper. Other material on the paper which may be minor amounts of endosperm cell walls, incompletely dispersed starch, or incompletely dispersed protein are colorless. Bran and germ particles are, therefore, easily identified, and the deposited material may be observed wet or dry. The determination may be conveniently accomplished visually. It may also be accomplished directly or indirectly by light transmittance, reflectance, colorimetric methods or similar methods familiar to skilled workers. For example, light reflected from a stained sample may be measured and recorded by photoelectric devices as an indication of the bran content.

45 Slight variations in the timing of various steps do not affect the result, and the procedure can be completed in about 1½ hours. The time may be 50 shortened by permitting the alkali to act for

about 15 minutes in the third step, then adding the distilled water and filtering immediately. This variation in procedure must be timed fairly accurately, lest the action of the alkali cause the germ and bran particles to become decolorized.

A useful variation of the invention can be employed to show the endosperm cell walls in wheat flour. Approximately 30 minutes after the water has been added in the fourth step, one ml. of about 0.1 percent aqueous Congo red stain is added to the mixture. This stains the endosperm cell wall particles an orange red. The sample should be examined in the staining solution. It is not practical to combine the two determinations on the same sample, however, for the bran and germ particles tend to stain orange red after contact with the Congo red for 20 to 30 minutes. Moreover, the filtration with filter paper tends to interfere with the results because the red dye stains the filter paper.

Observation of the violet stained bran and germ particles is preferably carried out microscopically. Both appear about the same under low magnification, but under high magnification, say of about 100X, the bran particles usually appear as flat pieces, while the germ particles appear as small, irregularly-shaped thick pieces. The evaluation is not absolute, however, for it is difficult to distinguish between very small particles of bran and of germ.

The following specific example illustrates the invention.

Example

One-gram samples each of patent, first clears and red dog flour were wetted with 95 percent ethyl alcohol. Each sample was then mixed with 18 ml. of 0.05 percent Crystal Violet and let stand for 10 minutes. Each was then mixed with 120 ml. of 1.0 percent (0.25 N) sodium hydroxide and let stand for five minutes, whereupon 140 ml. of distilled water was added and the mixture let stand for one hour. The mixture was then filtered on No. 1 Whatman filter paper, using a coarse fritted glass funnel.

The filter paper obtained from the red dog sample had a deep violet appearance. Microscopic examination revealed that the color was due to small particles of bran that had been dyed. The filter paper from the first clears sample was an intermediate shade of violet with a finely mottled appearance, the color being due to the presence of a considerable amount of dyed bran. The filter paper obtained from the patent sample had an overall tint of light violet, caused by individual particles of dyed bran peppered over the paper.

The number of steps set forth above represent preferred procedure. However, it is to be understood that the invention may be carried out in a wide variety of ways. The concentration of Crystal Violet dye must be kept within the designated limits.

Wetting the sample with ethanol or other denaturing agent is usually necessary for satisfactory results, for it prevents pasting and facilitates contact between the dye solution and the sample. It is only necessary that contact between the sample and the dye be sufficiently long to afford full staining. The amount of sodium hydroxide, or other alkali, may be increased or decreased compared with that specified in the numbered steps. However, the more alkali present, and the stronger it is, the faster the decolorization

process will be, and it is desirable that decolorization proceed at a rate slow enough to effect substantial decolorization of all substances present except the bran and germ particles.

5 I claim:

1. A method for determining bran and germ particle constituents in cereal flours comprising treating a given sample of flour material with a 0.04-0.07 percent aqueous solution of Crystal Violet whereby to dye bran and germ particles present in said flour material together with other material present, effecting differential decolorizing by treating the mixture with an aqueous solution of alkali until substantially all other constituents are decolorized, separating the solid material from the resulting alkaline solution and subsequently determining the amount of bran and germ particle constituents.

2. A method for determining bran and germ particle constituents in cereal flours comprising treating a given sample of flour material containing bran and germ particle constituents with a 0.04-0.07 percent aqueous solution of Crystal Violet whereby to dye at least said bran and germ constituents, treating said dye mixture with aqueous alkali to decolorize and substantially disperse the protein and starch constituents of said flour and separating the solid constituents from the alkaline aqueous solution before the bran and germ constituents become decolorized and subsequently determining the amount of bran and germ constituents.

3. The method comprising wetting a known quantity of cereal flour in aqueous ethanol, adding sufficient 0.04-0.07 percent aqueous solution of Crystal Violet to color the constituents of said cereal flour, adding alkali in sufficient quantity to decolorize differentially the starch, protein and endosperm cell wall material with respect to the bran and germ constituents and subsequently separating the colored bran and germ constituents from the aqueous dye solution before said bran and germ constituents undergo substantial decolorizing, and subsequently determining the content of bran and germ constituents by visual observation.

4. The method of claim 1 in which the treatment with aqueous alkali is carried out using 1.0 percent sodium hydroxide.

5. Method of claim 4 in which the alkaline treatment period is about 5 minutes and is followed by dilution of the mixture with about an equal volume of water and the diluted mixture permitted to stand for about 1 hour before separation of the insoluble constituents.

6. Method of claim 4 in which the alkaline treatment period is approximately 15 minutes followed substantially immediately by dilution with about an equal volume of water.

7. The method of rendering bran and germ particles, derived from cereal grains, visually distinguishable from other components of said cereal grains comprising subjecting a mixture of said particles and said other components to the action of a 0.04-0.07 percent aqueous solution of Crystal Violet dye followed by alkaline decolorization of said other components.
